FOOD STORAGE DISH

Robert Daenen, Erembodegem, Belgium, assignor to Dart
Industries Inc., Los Angeles, Calif.

Filed Apr. 19, 1972, Ser. No. 245,689

Term of patent 14 years

Int. Cl. D7—01

U.S. Cl. D7—16

FIG. - 1

FIG. - 2

FIG. - 3

FIG. - 4

FIG. - 5

FIG. - 6

FIG. 1 is a side elevational view of a food storage dish showing my new design;

FIG. 2 is an exploded end elevational view;

FIG. 3 is a top plan view of the dish closure;

FIG. 4 is a bottom plan view of the dish closure;

FIG. 5 is a top plan view of the dish base; and

FIG. 6 is a bottom plan view of the dish base.

I claim:

The ornamental design for a food storage dish, as shown.
